UNITED STATES PATENT OFFICE.

CHARLES O. WHITNELL, OF DES MOINES, IOWA.

DESIGN FOR A VENTILATOR.

59,879.

Specification for Design.

Patented Nov. 29, 1921.

Application filed January 28, 1919. Serial No. 273,656. Term of patent 3½ years.

To all whom it may concern:

Be it known that I, CHARLES O. WHITNELL, a citizen of the United States, and a resident of Des Moines, in the county of Polk and State of Iowa, have invented a new, original, and ornamental Design for a Ventilator, of which the following is a specification, reference being had to the accompanying drawing, forming part thereof.

The figure shows a perspective view of a ventilator embodying my invention.

I claim:

The ornamental design for a ventilator, as shown.

Des Moines, Iowa, September 5, 1918.

CHARLES O. WHITNELL.
